US0D1112233S

(12) **United States Design Patent** (10) **Patent No.:** **US D1,112,233 S**
(45) **Date of Patent:** **** Feb. 10, 2026**

(54) **CASE FOR ELECTRONIC DEVICE**

(71) Applicant: **Samsung Electronics Co., Ltd.**, Suwon-si (KR)

(72) Inventors: **Dongkyun Kim**, Suwon-si (KR); **Minah Koh**, Suwon-si (KR)

(73) Assignee: **SAMSUNG ELECTRONICS CO., LTD.**, Gyeonggi-Do (KR)

(**) Term: **15 Years**

(21) Appl. No.: **29/972,042**

(22) Filed: **Nov. 7, 2024**

(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

Broken lines and adjacent unshaded surfaces illustrate portions of the case for electronic device that form no part of the claimed design.

1 Claim, 6 Drawing Sheets
